REPEATING CIRCUIT INTERRUPTER WITH
FLUID INTEGRATING MEANS

Max Rigert, West Allis, Wis., assignor to McGraw-Edison
Company, Milwaukee, Wis., a corporation of Delaware
Filed Apr. 9, 1962, Ser. No. 186,079
6 Claims. (Cl. 200—89)

This invention relates to repeating circuit interrupters of the type commonly known as reclosers.

It is common practice to utilize a variety of protective devices having time current characteristics of different shapes and slopes in a single electrical system. For example, a distribution system may be provided with a recloser connected in series with the main line and located adjacent the source of power and fuses disposed in feeder lines radiating from the main line. Because the majority of faults in such systems are temporary in nature, and will, therefore, clear in a relatively short time, it is common to arrange the repeating circuit interrupter to execute a series of rapid opening and reclosing operations so that the period in which the system remains energized is shorter than the time necessary for the fuse elements to melt. If the fault does not clear during this initial series of rapid operations, it is considered permanent and there follows a second series of operations in which the recloser contacts remain closed for a period of sufficient length to melt the fuse element in the faulted feeder line. If the fault clears due to the melting of the fuse or for some other reason during any of these successive operations, the recloser closes to maintain power in the main line and in the non-faulted feeder lines. If, on the other hand, the fault is not cleared during this series of rapid and retarded opening operations, the recloser automatically locks out to disconnect the main line from the source. In order to properly coordinate a particular recloser with other protective devices the number of opening operations prior to lockout must be conveniently and accurately preselectable.

As the use of electric power increases in existing distribution systems it becomes necessary, from time to time, to increase the ratings of existing systems. This requires the installation of higher rated transformers and reclosers to accommodate this increased load. In order to minimize the cost of such upgrading of existing systems, it is desirable to provide protective equipment which can be mounted on poles or other supporting structures originally designed for lower rated devices.

It is an object of the invention to provide a recloser having new and improved operation counting and lockout apparatus.

Another object of the invention is to provide a repeating circuit interrupter having operation counting and lockout means which are easily and quickly adjustable.

A further object of the invention is to provide an oil-immersed repeating circuit interrupter having hydraulic operation counting and lockout means which does not require long insulating links.

It is yet another object of the invention to provide a repeating circuit interrupter having compact operating mechanism which allows a higher rated device to be housed in a container customarily used with lower rated devices.

These and other objects and advantages of the instant invention will become more apparent from the detailed description thereof taken with the accompanying drawings in which:

FIG. 1 is an elevational view, with parts broken away, of a reclosing circuit interrupter assembly embodying the instant invention;

FIG. 2 is a schematic diagram of the operating mecha-

2

nism of the reclosing circuit interrupter illustrated in FIG. 1;

FIG. 3 is a side elevational view partly in section illustrating the reclosing solenoid of the recloser of FIG. 1;

FIG. 4 is a side elevational view partly in section of the integrating mechanism according to the instant invention;

FIG. 5 is a view taken along lines 5—5 of FIG. 4;

FIG. 6 is a view taken along lines 6—6 of FIG. 4;

FIG. 7 is a view taken along lines 7—7 of FIG. 4;

FIG. 8 is a view taken along lines 8—8 of FIG. 3;

FIG. 9 is a view taken along lines 9—9 of FIG. 8; and

FIG. 10 schematically illustrates the electrical circuit of the recloser shown in FIG. 1.

Referring more specifically to FIG. 1, the circuit interrupter incorporating the instant invention includes a metallic tank 10 filled with dielectric fluid, such as oil, to a level indicated by the phantom line 11, and provided with a gasketed cover 12. The cover 12 is provided with a pair of bushings 13 which extend interiorly of the tank 10 and beneath the oil 11 for connection to conductors 14, for the purpose of serially connecting the recloser in the system being protected. As seen in FIG. 10, the current path through the recloser between the bushings 13, constitutes a series circuit including the conductors 14, an electromagnetic tripping relay 16 and an interrupting switch means generally designated by the reference numeral 18.

The following will, in general terms, be a discussion of the circuit interrupter illustrated in FIG. 1 for the purpose of correlating the various portions of the device illustrated in the drawings.

When an overcurrent exists in the system being protected, the overcurrent relay 16 operates to release a linkage assembly 20, illustrated in greater detail in FIG. 2, upon which event the interrupting switch means 18 of FIG. 1 is opened and series relay 16 is de-energized. When the switch means 18 reaches its fully opened position, a potential coil 22 is placed in circuit between the line being protected and ground so that it attracts a magnetic plunger 24 downwardly to reclose the switch means 18 through the agency of the operating mechanism 20. Should the fault persist, the series relay 16 will again operate to initiate a switch opening operation in the manner above described.

Each opening of the switch means 18 causes the pump piston 28 of an integrating assembly 27, see FIG. 5, to deliver a measured quantity of hydraulic fluid under an integrating piston 26 which elevates in a step by step manner and accordingly, causes similar advancement of a trip stem 122 to which it is connected by a pin 123. After a predetermined number of such opening operations, usually four, the stem 122 has advanced to where it causes the operation of a lockout mechanism 32, as seen in FIG. 2, which prevents the further energization of the potential coil 22 so that further reclosure of the device is prevented.

Referring again to FIG. 1, the operating mechanism 20 is shown mounted on a chassis 34 which is suspended from the cover 12 by integral bosses 36. Also mounted on the chassis 34 and below the operating mechanism 20, is the hydraulic integrating mechanism 27.

The closing potential coil 22 is wound on a flanged spool mounted between the flange of a collar member 39 and a plate 40 which are, in turn, supported below the chassis 34 by insulating stringers 42. In a similar manner, insulating plate 44 is suspended from the metallic plate 40 by insulating stringers 45 and supports the overcurrent relay 16 on its upper surface and the interrupting chamber 47 for the switch mechanism 18 from its lower end.

The overcurrent relay 16 includes a coil 49, a core 50 and a magnetic plunger 52 connected to the operating mechanism 20 by a pair of long insulating links 53. As

seen in FIG. 2, the upper end of the links 53 are pivotally connected to a lever 55 of the operating mechanism 20. When the current in overload coil 49 exceeds its rated value, the magnetic plunger 52 is attracted downwardly causing a downward movement of the vertical links 53.

Referring again to FIG. 2, vertical movement of the links 53 cause the clockwise rotation of the lever 55 which, in turn, rotates a trip shaft 56 to affect tripping of the device in the manner to be described.

Referring now to FIG. 3, the movable contact portion 58 of the interrupting switch mechanism 18 is carried at the lower end of a long vertical insulating link 59 which is connected at its upper end to one leg of a bell crank 61 through a short intermediate link 62, shown in FIG. 2.

The bell crank 61 is adapted to pivot on a fixed pivot 64 and is connected at its other leg to the switch opening spring 66. Under normal circuit conditions, when the recloser is closed, the opening spring 66 tends to rotate the bell crank 61 clockwise to force the link 59 downwardly and thereby open the main switch means 18. Such opening action is normally prevented, however, by a collapsible general latch means or toggle link assembly designated by the reference numeral 67.

When the recloser is closed, the toggle link assembly 67 effects a rigid connection between the bell crank 61 and a rocking lever 69, the latter of which is normally latched and participates in a switch resetting operation as will be explained hereinbelow. The toggle link assembly 67 comprises a long link 70 pivotally connected near its mid section to a triangularly shaped link 72 which in turn is pivotally connected to the rocking lever 69 at 73.

The tendency is for the elongated link 70 to rotate in a clockwise direction under the influence of opening spring 66 acting on the bell crank 61, but this is normally prevented by a semicylindrical latch shaft 75 that is pivotally mounted on triangular link 72 and which acts as a stop for the link 70.

The half shaft 75 is provided with an arm 77 having an aperture 78 at its free end. A spring 80 urges the arm 77 and the semicylindrical latch 75 in a counterclockwise direction until the edge of the aperture 78 engages a stop pin 79 extending from the triangular link 72. This holds the outer periphery of the semicylindrical latch 75 in engagement with the tip of the long link 70 to maintain the latter in its latched position. Thus, if the half shaft 75 is rotated clockwise as viewed in FIG. 2, the tip of link 70 will move past the flattened portion of said half shaft and allow rotation of the links 70 and 72.

As stated hereinabove, operation of the overcurrent relay 16 will move the links 53 downwardly to rotate the trip shaft 56 clockwise. This moves the upper end of a trip arm 82, as viewed in FIG. 2, into engagement with the left end of a long link 83 carried at the lower ends of links 84 and 84'. Link 84 is pivotally mounted at fixed point 85 while link 84' is received on a manual operating shaft 86. Engagement of the link 83 by the arm 82 moves an offset portion 87 of the former into engagement with the arm 77 rotating shaft 75 against the influence of spring 80. The tip of link 70 is thus allowed to move past the flattened portion of shaft 75 so that the toggle links 70 and 72 are free to rotate. Upon this event, the bell crank 61 rotates clockwise through a limited angle opening the interrupting switch 18.

When the toggle link assembly 67 collapses and the bell crank 61 rotates to open interrupting switch 18, rocking lever 69, which is affixed to a rocking shaft 88, remains stationary temporarily because it is normally latched by a spring-biased lever 89 carried on a fixed pivot point 92 and engaged at 93 with an end of the rocking lever. However, when the bell crank 61 has nearly completed its clockwise rotation, a pin 95 extending transversely therefrom strikes latch lever 89 and releases rocking lever 69 for clockwise rotation under the influence of a spring 96. This elevates the closing magnetic plunger 24 which is connected to the rocking lever 69 by a pair of insulating links 98.

Clockwise rotation of rocking lever 69 also immediately aligns the triangular link 72 and the long link 70 of the toggle link assembly 67 and allows the tip of link 70 to move upward past the flattened edge of half shaft 75 and to catch again on the edge of the outer periphery thereof. This restores the toggle link assembly to rigid condition, but in a lower position, so that when rocking lever 69 is subsequently rotated counterclockwise by descent of plunger 24, the toggle assembly 67 will drive bell crank 61 counterclockwise and thus extend opening spring 66. This not only closes the interrupting switch 18, but also reloads the opening spring 66 in preparation for another opening operation.

Closing of the interrupting switch 18 is achieved by the movement of the closing magnetic plunger 24 downwardly through the agency of resetting coil 22. Coil 22 is in circuit with an auxiliary switch, designated generally by the reference numeral 100, that completes an energizing circuit to the coil 22 when the plunger 24 is in its uppermost position and reopens the coil circuit when the plunger 24 is in its lowermost position.

Coil 22 is supplied with line to ground voltage by being connected across the conductors 14, as seen in FIG. 10, through wires 102 which are in series with the contacts 103 of auxiliary switch 100, see FIG. 2. Auxiliary switch 100 is operated from the rocking shaft 88 to which rocking lever 69 is rigidly affixed. When shaft 88 rotates through a limited angle after the main switch 18 opens it oscillates an arm 104 through a like clockwise angle for actuating switch 100 from open position as shown to a closed position. For this purpose, arm 104 is slotted at 105 for loosely and slidably engaging a pin 106 that is carried by a link 107. The latter link 107 is moved on a stationary pin 108 and on the same pin there is also pivotally supported another link 109 to which an insulating rod 110 is pinned at 111. Links 107 and 109, together with a spring 112, constitute an overcenter linkage for operating switch 100 with a snap action.

It will be seen that when arm 104 is rotated clockwise, pins 106, 108 and 111 will first form a straight line coincident with the line of action of spring 112 which will then be stretched and pre-loaded. As sliding pin 106 is carried further counterclockwise, spring 112 is able to contract and lift link 109 in a clockwise direction whereupon contacts 103 are bridged and coil 22 is temporarily energized. Plunger 24 is immediately drawn downward by coil 22 to close the interrupting switch 18 and to open the switch 100 by an action of over-center spring 112 converse to that just described. Latch 89 then engages rocking lever 69 to hold plunger 24 down.

As seen in FIG. 3, the closing magnetic plunger 24 has a central bore 115 to permit the passage of the link 59, connected to the movable contacts 58, to pass therethrough. In addition, it can be seen that the plunger 24 resides in a dashpot 118 which is surrounded by the potential closing coil 22. The initial portion of the upstroke of plunger 24 is retarded as the oil is trapped beneath the plunger and has to be supplied through a small orifice 119 in a check valve 120 (see FIG. 9) which is biased upwardly by a spring 121 to normally substantially close the lower portion of the dashpot cylinder 118. The check valve 120 freely opens downwardly and the plunger 24 has a relatively rapid downward stroke, cushioned by the oil in cylinder 118, and thus serves to quickly close the main switch 18. The upward stroke, however, is retarded and this provides a time delay for the circuit interrupter when it is closed after an opening operation.

This symmetrical arrangement of the magnetic plunger and contact link 59 permits a more compact operating assembly than in prior art devices wherein the closing coil had to be mounted in an offset position relative to the main interrupting contacts. As a result the tank 10 may be of the same relative size as lower rated devices not having a closing coil but relying on springs to provide this function.

It will be appreciated by those skilled in the art that

when an arc is interrupted in an oil-immersed interrupter, such as 47 shown in FIGS. 1 and 3, gas bubbles consisting of products of decomposed oil will be exhausted from the ports 230. These bubbles will tend to rise toward the upper end of the tank 10 and in order to prevent them from being drawn into the dash-pot cylinder 118 when the piston 24 rises, a semi-cylindrical baffle 231 is affixed over the orifice 119.

A small aperture 232 in the baffle 231 permits the passage of the link 59. The baffle not only deflects the bubbles emitted from the interrupter 47 but also holds a pocket of oil adjacent the orifice 119. This lessens the tendency for a gas pocket to collect in the cylinder 118 and thereby create erratic movements of the plunger 24.

Lockout means are provided for preventing reclosure of the apparatus if the fault does not clear after a predetermined number of opening operations, usually four. The lockout means includes the integrating assembly 27 which constitutes a portion of the instant invention and which will be described in greater detail hereinafter. It will be sufficient at this point to state that the pump piston 28 of the mechanism 27 is connected by a pin 29 to a stem 30 which in turn is connected to the rocking lever 69. As a result, pump piston 28 is driven by angular gyrations of the rocking lever 69 each time the recloser operates. The output of the pump piston 28 is delivered to the pressure side of an integrating piston 26. As the recloser operates repeatedly, the integrating piston 26 is forced hydraulically upward in a step by step manner causing a corresponding movement of a lockout stem 122 which is attached thereto.

The lockout stem 122 is connected at its upper end, through the agency of an arm 124, to a U-shaped lockout bar 125 whose opposite ends are pivotally mounted at 126 and 126' on the chassis 34. Each time the lockout stem 122 advances it rotates the lockout bar 125 through a counterclockwise angle as viewed in FIG. 2.

Lockout of the recloser is brought about by a lever 127 pivoted on a stationary pivot 128 that depresses the auxiliary switch link 110 and thereby prevents energization of the closing coil 22 until manually reset. The angular position of the lever 127 is controlled by an elongated link 129 which is positioned by a latch mechanism generally designated by the reference numeral 130 and which includes a latch crank 132 received on the shaft 86 and having a tip 133 which normally bears on the outer periphery of a semicylindrical latch 134. The latch 134 is carried by a link 135 which is pivoted about the fixed point 136. The link 135 and the latch 134 are held in the position shown in FIG. 2 by a spring 137.

After a predetermined number of opening operations, a pin 138 extending laterally from one of the arms of the lockout bar 125 will strike the latch lever 135 rotating the half moon latch 134 counterclockwise around pivot point 136 to release the latch crank 132 and the shaft 86 for counterclockwise rotation by spring 140. This moves the link 129 downwardly, as viewed in FIG. 2, to rotate the crank 127 counterclockwise into engagement with the upper end of the auxiliary switch link 110 to prevent closure of the latter and thereby effect lockout.

Resetting of the device is accomplished by clockwise rotation of an arm 142 affixed to the shaft 86, which in turn elevates the link 129 and relatches the tip 133 of crank 132 on latch 134. The secondary switch 100 is thereby freed to energize the closing coil 22.

The illustrated recloser is characterized by a dual time current characteristic, that is, the recloser is adapted to open instantaneously on the first of a series of opening operations and then to open with a time delay on subsequent operations prior to lockout. To accomplish this, the hydraulic time delay mechanism designated generally by the reference numeral 149 is provided. The specific details of the time delay mechanism 149 form no part of the instant invention and accordingly will not be described in detail. For a more complete description of time delay mechanism 149 reference is made to U.S.

Patent 2,907,562 to A. Van Ryan et al. and assigned to the assignee of the instant invention.

As seen in FIG. 2, the lever 55, to which the upper end of the link 53 is pivotally connected, is connected at its free end to a hook shaped time delay latch finger 150 which extends generally upward. Latch finger 150 is biased clockwise with respect to lever 55 by a spring 152 but such rotation is normally opposed by a cross pin 153 lying in the swinging path of finger 150 and carried by a lever 155 which is pivoted about a fixed pin 156. In order to render the time delay device 149 effective to delay tripping by retarding the downward movement of link 53, the latch finger 150 must be allowed to engage a pin 158 extending transversely through the time delay lever 159 pivotally mounted at 160 on a bracket 162 extending upwardly from the body of the time delay mechanism 149.

As long as the time delay control bar 164 remains in the position in which it is shown in FIG. 2, the biasing influence of spring 152 is overcome and the hooked end of the latch finger 150 is free to move downwardly without engaging pin 158. Thus, in the first series of operations link 53 may descend without retardation because time delay arm 159 is disconnected from the latch finger 150.

The influence of the time delay device 149 is brought into effect by shifting a timing bar 164 to the left in opposition to a spring 166 to rotate the lever 155 clockwise and to move the pin 153 away from the latch finger 150 so that the latter is free to be rotated clockwise by the spring 152 until it engages the pin 158. Displacement of timing bar 164 in this manner is accomplished through the agency of an indexing wheel 167 rotatably mounted at 126 and a lever 168.

The indexing wheel 167 is coupled to the integrating bar 125 by an indicating arm 170 which is affixed to one of the legs of said integrating bar. A driving connection is formed between the wheel 167 and the arm 170 by a transverse indexing pin 171 which is receivable in one of a plurality of indexing holes 172 adjacent the periphery of indexing wheel 167. Indicia 174 are provided adjacent the periphery of indexing wheels 167 at its opposite side for cooperating with the pointer 175 to indicate the number of time delay operations which will occur. By removing the pin 171 from one of the holes 172 and rotating the wheel in one direction or the other, the edges 45 of the recess 177 will be moved relative to roller 179 thereby changing the number of operations necessary to initiate time delayed operation. Reinsertion of the pin 171 in the hole 172 corresponding to this position reestablishes the driving connection.

It can be seen that rotation of the timing bar 125 in a counterclockwise direction will move the edge of a recessed portion 177 of the indexing wheel 167 into engagement with a roller 179 carried on the free end of the lever 168 to rotate the latter and thereby displace the timing bar 164 toward the left to initiate time delayed operation.

Referring now specifically to FIGS. 4-7, the integrating mechanism 27 is shown to include a block portion 182 forming a housing and having a pair of cylindrical recesses 184 and 186 which provide cylinders for reciprocally receiving the pump piston 28 and the integrating piston 26, respectively. A third recess 187 acts as a sump for the hydraulic fluid of the mechanism 27. A gasketed cover plate 188 is affixed to the upper end of the block or housing 182 to seal the assembly 27. In addition, sealing assemblies 189 are provided in cover 188 to seal the openings around the stems 30 and 122.

As seen in FIG. 5, a recess 190 is formed in the block 182 below the integrating cylinder 186 and is connected to said cylinder through a ball check valve 191. Also, the recess 190 is connected to the pump cylinder 184 by passages 192, 193 and 194 (see FIG. 7). The lower end of the pump cylinder 184 is also connected to the lower end of the sump 187 through a passage 196 and a ball check valve 198. In addition, ports 200 and 201,

respectively, connect the upper ends of the integrating cylinder 186 and the pump cylinder 184 to the sump 187. A second port 203 near the lower end of the pump cylinder 184 also opens into the sump 187.

As seen in FIG. 5, the pump piston assembly 28 includes an externally threaded body 205 which is threadably received into an internally threaded sleeve 206. It can be seen that the axial length of the body 205 is shorter than the sleeve 206. A pin extends across the lower end of the sleeve 206 and is rigidly affixed thereto for the purpose of rotating the sleeve relative to the body 205 so that the relative axial position of the sleeve and the body may be adjusted.

Rotation of the sleeve 206 is accomplished by a rod 210 extending through a bore 211 formed in the housing 182 and opening into the lower end of the cylinder 184. The rod 210 is provided with a head 212 having a slot 214 for embracing the pin 208. Thus, when rotation of the sleeve 206 is desired the piston assembly 28 is depressed to the lower end of the chamber 184, a threaded plug 215 covering the outer end of the bore 211 is removed, the slot 214 is engaged with the pin 208 and the rod 210 is rotated to rotate the sleeve 206. Because the body 205 is rigidly affixed to the stem 30 by the pin 29, rotation of the sleeve 206 will cause relative axial movement between the body 205 and said sleeve. The purpose for this adjustment will be more fully appreciated when operation of the integrating assembly is discussed in detail hereinbelow.

As seen in FIGS. 2 and 4, the upper end of the pump piston stem 30 is connected through the agency of a pair of links 216 to the rocking lever 69. Thus, each time the rocking lever pivots, after a switch opening operation, the pump piston assembly 28 is depressed in cylinder 184 to force a measured quantity of hydraulic fluid through the passages 192, 193 and 194, past the ball check valve 191 and below the integrating piston 26 elevating the latter.

The integrating piston stem 122 is connected by links 218 to the lockout bar 125. As a result, elevation of the integrating piston 26 rotates the lockout bar 125 in a counterclockwise direction as viewed in FIG. 2.

It will be recalled that when the interrupting switch 18 is reclosed by the descent of the magnetic plunger 24, the rocking lever 69 is returned to its original unrotated position. This raises the pump piston assembly 28 to its original elevated position shown in FIG. 5 whereupon hydraulic fluid is drawn from the sump 187 through the ball check valve 198. As a result, the pump piston assembly 28 is in position to force a second measured quantity of oil beneath the integrating piston 26 should a succeeding opening operation occur. In this manner the integrating piston 26 is advanced in a step by step manner until the lockout bar 125 has been rotated sufficiently to cause lockout. If the number of operations are insufficient to cause lockout, the integrating piston 26 will slowly settle to its initial position so that the integrating assembly is reset. This rate of resettlement is not, however, rapid enough to affect the number of operations during the normal operating sequence.

It can be seen that because the port 203 opens directly into the sump 187 no fluid will be pumped beneath the integrating piston 26 until the lower edge of the sleeve 206 completely covers said port. Thus, fluid will be pumped under the piston 26 only for that portion of the pump piston stroke subsequent to the passage of the sleeve 206 over the port 203. Because the body 205 is rigidly affixed to the stem 30, its descent in the cylinder 184 will be fixed regardless of its axial position relative to the sleeve 206. Thus, by moving the sleeve 206 downward in relation to the body 205, it will be made to cover the port 203 for a greater portion of the downward stroke so that a larger quantity of oil will be pumped beneath the integrating piston 26. Conversely, movement of the sleeve 206 axially upward relative to the body 205

will decrease the working stroke of the piston assembly 28. However, because the stroke of the piston assembly 28 remains constant, increasing or decreasing its working portion has the effect of increasing or decreasing the amount of fluid pumped beneath the integrating piston 26. As a result, it is possible to accurately adjust the distance the integrating piston 26 will be elevated for each opening operation of the device. Thus, initiation of the time delay and lockout operations by the integrating piston can be accurately adjusted.

A friction plug 220, disposed in a transverse recess 222 formed in the body 205 and urged outwardly against the threads of the sleeve 206, prevents rotation of said sleeve during normal operation of the assembly 27.

It will be appreciated that by providing a completely self contained hydraulic assembly 27 having its own supply of hydraulic fluid, it is not necessary to submerge the assembly 27 in the dielectric fluid 11 so that long insulating members for connecting the pump piston stem 30 and the integrating piston stem 122 to the operating mechanism 20 are not needed. The completely self contained unit has the additional advantage in that bubbles, inherent in the fluid 11 during a fault interruption, will not be drawn into the pump and integrating cylinders and thereby produce erratic movement of their respective pistons.

While only a single embodiment has been shown and described it is not intended that the invention be limited thereto but only by the scope of the appended claims.

I claim:

1. A repeating circuit interrupter for protecting an electrical system and including a casing containing a quantity of dielectric fluid, switch means disposed in the lower end of said casing and beneath said dielectric fluid, operating means disposed near the upper end of said casing and above said dielectric fluid, a link extending downward from said operating means for connecting the latter to said switch means, said operating means including resilient means urging said switch means toward an open position and latch means for holding said switch means closed in opposition to said resilient means, trip means for releasing said latch means upon the occurrence of a predetermined condition in said system, electromagnetic reclosing means disposed between said operating means and said switch means and including a coil energizable after each opening operation of said switch means and a plunger having a bore extending therethrough for permitting said link to pass therethrough, said plunger being connected to said operating means independently of said link for being moved upwardly during each opening operation, said plunger being attracted downwardly into said coil upon the energization of the latter to relatch said switch means.

2. A repeating circuit interrupter including a sealed casing containing a quantity of dielectric fluid, switch means disposed in the lower end of said casing and beneath said dielectric fluid, operating means disposed near the upper end of said casing and above said dielectric fluid, a long link extending downward from said operating means for connecting the latter to said switch means, said operating means including spring means urging said switch means toward an open position and latch means for holding said switch means closed in opposition to said spring means, overcurrent responsive trip means for releasing said latch means, electromagnetic reclosing means disposed beneath said fluid and including a coil energizable after each opening operation of said switch means and a plunger, a dashpot cylinder disposed interiorly of said coil for receiving said plunger through its upper end when the latter is attracted by said coil to retard the movement of said plunger, said plunger having a bore extending therethrough and said dashpot having an aperture at its lower end for permitting said long link to pass therethrough, whereby said long link and said plunger may move in-

dependently of each other, said plunger being connected to said operating means to relatch said switch means upon being attracted downwardly into said dashpot by said coil.

3. A repeating circuit interrupter including a sealed casing containing a quantity of dielectric fluid, switch means disposed in the lower end of said casing and beneath said dielectric fluid, operating means disposed near the upper end of said casing and above said dielectric fluid, a long link extending downward from said operating means for connecting the latter to said switch means, said operating means including spring means urging said switch means toward an open position and latch means for holding said switch means closed in opposition to said spring means, overcurrent responsive trip means for releasing said latch means, electromagnetic reclosing means disposed beneath said fluid and including a coil energizable after each opening operation of said switch means and a plunger, a dashpot cylinder disposed interiorly of said coil for receiving said plunger through its upper end when the latter is attracted by said coil to retard the movement of said plunger, said plunger having a bore extending therethrough and said dashpot having an aperture at its lower end for permitting said long link to pass therethrough, said plunger being connected to said operating means for being moved upwardly during each opening operation, said plunger being attracted downwardly into said dashpot by said coil upon the energization of the latter to relatch said switch means, said fluid being drawn into and expelled from the aperture in said dashpot during the upward and downward movement of said plunger, and baffle means disposed below said aperture to prevent the entrance into said dashpot of bubbles incident to the interruption of a circuit by said switch means beneath said fluid.

4. For use in a repeating circuit interrupter having switch means, operating means for opening and reclosing said switch means and lockout means for preventing the reclosure of said switch means after a predetermined number of opening operations, the combination of a self-contained hydraulic integrating assembly comprising a sealed housing having first and second cylinders and a sump cavity formed therein, a quantity of hydraulic fluid disposed within said sump cavity, pump piston means disposed in said first cylinder, integrating piston means disposed in said second cylinder, valve means for connecting the pressure side of said pump piston means to said integrating piston means when said pump piston means is descending and for connecting the pressure side of said pump piston means to said sump when said pump piston means is ascending, said pump piston means being mechanically connected to said operating means for depression upon each switch opening operation so that a measured quantity of hydraulic fluid is pumped beneath said integrating piston, a by-pass passage connected to said sump cavity and opening into said first cylinder intermediate its ends for by-passing a portion of said pumped fluid around said integrating cylinder, said pump piston including closure means for closing said by-pass passage after said piston begins descending, means extending through said housing and operable externally of said integrating assembly for adjusting the relative proximity of said closure means to said passage independently of the stroke of said pump piston so that the quantity of fluid delivered to said integrating cylinder upon each opening operation may be adjusted.

5. For use in a repeating circuit interrupter having switch means, operating means for opening and reclosing said switch means and lockout means for preventing the reclosure of said switch means after a predetermined number of opening operations, the combination of a self-contained hydraulic integrating assembly comprising a sealed housing having first and second cylinders and a sump cavity formed therein, a quantity of hydraulic fluid disposed within said sump cavity, pump piston means

disposed in first cylinder, an integrating piston disposed in said second cylinder, valve means for connecting the pressure side of said pump piston means to said integrating piston when said pump piston means is moved in one direction and for connecting the pressure side of said pump piston means to said sump when said pump piston is moved in the opposite direction, said pump piston means including an internal body member and an external sleeve member adjustably mounted on said body member, said body member being mechanically connected to said operating means for movement in one direction upon each switch opening operation so that a measured quantity of hydraulic fluid is pumped to said integrating piston, a by-pass passage connected to said sump cavity and opening into said first cylinder intermediate its ends for by-passing a portion of said pumped fluid around said integrating cylinder, said sleeve member being operative to close said by-pass passage after said pump piston means begins moving in said first direction, means extending through said sealed housing and operable externally of said integrating assembly for adjusting the relative position of said sleeve member on said body member so that the initial proximity of said sleeve member relative to said passage may be changed independently of the stroke of said pump piston whereby the quantity of fluid delivered to said integrating cylinder may be adjusted.

6. For use in a repeating circuit interrupter having a sealed casing, a quantity of dielectric liquid disposed within said casing, switch means disposed beneath said liquid, operating means for opening and reclosing said switch means and lockout means for preventing the reclosure of said switch means after a predetermined number of opening operations, the combination of a self-contained hydraulic integrating assembly comprising a sealed housing having first and second cylinders and a sump cavity formed therein, a quantity of hydraulic fluid disposed within said sump cavity, pump piston means disposed in said first cylinder, an integrating piston disposed in said second cylinder, the upper end of each of said cylinders being connected to said sump cavity, valve means for connecting the lower end of said pump piston means to the lower end of said integrating piston when said pump piston means is descending and for connecting the lower end of said pump piston means to said sump when said pump piston means is ascending, said pump piston means being mechanically connected to said operating means for depression upon each switch opening operation so that a measured quantity of hydraulic fluid is pumped beneath said integrating piston, a by-pass passage connected to said sump cavity and opening into said first cylinder intermediate its ends for by-passing a portion of said pumped fluid around said integrating cylinder, said pump piston means including a body and closure means for closing said by-pass passage after said piston begins descending, said closure means being rotatable relative to said body for changing its proximity relative to said passage independently of the stroke of said pump piston so that the quantity of fluid delivered to said integrating cylinder may be adjusted, and means extending through said housing for engaging said closure means to rotate the same from a point external of said integrating assembly.
